ATTORNEY

UNITED STATES PATENT OFFICE

JOHN SWENEHART, OF WILMINGTON, DELAWARE, ASSIGNOR TO ATLAS POWDER COMPANY, OF WILMINGTON, DELAWARE, A CORPORATION OF DELAWARE

BLASTING ASSEMBLY

Application filed April 25, 1931. Serial No. 532,942.

This invention relates to blasting assemblies and it has for its object to provide a blasting unit adapted to be placed upon the market as an article of manufacture and assuring to the user the delivery of an assembly which in every phase of its makeup is so constructed as to assure a maximum of convenience, economy and safety in use.

The assembly of the present invention 10 provides markedly decreased hazards and increased convenience in use, improved protection against moisture, improved economy of consumer time, and elimination of many of the effects of consumer carelessness and ignorance.

Under existing methods a blaster must purchase and be provided with a box of blasting caps, a roll of fuse, a cap crimper, and means for igniting the fuse. Under my 20 proposed invention I substitute a single package containing the caps crimped on the fuses under conditions which secure the maximum effective and safe results, each of said fuses being provided at its free end with 25 a waterproofing material or a material which combines capability of waterproofing with ready inflammability to insure ease of ignition from some simple source, such as a match, for example.

Under existing practice blasting caps are 30 practically always shipped and handled in a metallic box having a slip cover. These boxes do not provide protection against moisture. Further, these relatively small boxes are easily misplaced; many users do not remove the caps from the boxes in a safe manner and the exposed charge is very sensitive and hazardous under careless handling.

It is easy to accidentally drop from the box 40 a cap which might be found by children or others unfamiliar with its character and its dangerous nature.

The commonly employed safety fuse is sold in coils wrapped in paper. There are always 45 two open ends at which the ignitable train

may be damaged by moisture. The instructions given by the manufacturers of safety fuses are to cut a piece from the end to eliminate possibly damaged fuse, before taking a section for use. Failure to do so may mean 50 misfire, inefficiently exploding caps or difficulty in igniting the fuse, with considerable resultant hazards. For instance, when a series of rounds are being set off, the operator must not spend too long a time at each fuse. 55 Further, tightly coiled fuses may be damaged by unwinding in cold weather. Cap crimpers properly used are essential for the proper combination of the cap and fuse, yet many consumers use the crimpers improperly or have none at all when needed, using 60 their teeth, a pen knife, a piece of rock or other hazardous and unsatisfactory measures to crimp the cap on the fuse.

A further source of possible danger resides in the failure of the user to cut the fuse off squarely so that its butt end sets squarely 65 on the cap composition. Very frequently the user cuts the end of the fuse off at an angle and in such manner that it seats only 70 partially on the cap composition. This frequently causes a failure of the charge to explode.

It is difficult to ignite the end of a fuse, even when the fuse is in perfect condition 75 and it is common practice for the users to split the end of the fuse with a pen knife to expose the powder train in an endeavor to bring about ready ignition. Even without this expedient it is frequently impossible to 80 bring about ignition from a single match flame and especially is this true if the wind is blowing.

It is frequently the case that the blaster 85 must make several attempts and light several matches before ignition is effected. This is not so serious a matter where only one charge is to be set off, but where a number of rounds have to be fired the delay in effecting ignition compels the blaster to remain too long near a 90

previously ignited fuse and has resulted in many serious accidents. In an endeavor to avoid this difficulty users have been known to employ torches consisting of a kerosene 5 soaked rag on the end of a stick for effecting ignition of the fuse. Obviously it is difficult to see the spit of the fuse through the smoke and flame of the torch and consequently it is difficult to know when lighting has been accomplished. Gasoline blow torches have also 10 been used for the purpose indicated. However, the noise from such torches prevents the sound of the fuse spit from being heard. A very considerable number of accidents have 15 occurred from such devices, the final dynamite charge exploding before the blaster knew that the fuse was ignited. Further, such large masses of flame are in themselves dangerous around explosives.

20 It is generally recognized that electric blasting caps are safer in transportation and handling than ordinary blasting caps, because of the cushioning effect of the wires. In like manner, with my new assembly, the caps are 25 cushioned in their packages by the presence of and are separated by the fuse.

If a child or ignorant person should find a cap with a fuse tightly affixed to it, they would be more impressed with its potentialities for danger than by the blasting cap alone. In addition they could not so easily prod into the cap with a nail as is often the case. Many of the difficulties outlined above have been long recognized but the method of 30 use of cap and fuse has remained unchanged. I propose by my present invention to bring about a combination of conditions which will meet every objection and insure the desirable results above outlined.

40 At the blasting factory the caps and fuse are stored under ideal conditions until it is desired to assemble them. In a dry building proper fuse lengths are cut, ends which have had air exposure being discarded. A flatly 45 cut fuse end is inserted in each cap, gently but to a snugly seated fit. Proper crimpers are used to bind the cap to the fuse, forming a difficultly breakable and moisture tight union. There still remains an open fuse end.

50 This may be protected by dipping in a sealing compound, as molten tar which is solid when cold. This bead of tar protects against moisture absorption at any time, and when cut off exposes a dry fuse end for lighting.

55 Preferably, this fuse end protection is a moisture resistant composition which will ignite from the least touch of a match flame and will in turn ignite the fuse. Such compositions may be suspended in nitrocellulose 60 lacquer and applied by dipping the fuse end in the pasty mass. Suitable, but not limiting compositions are:

75%—25% tetryl—potassium dichromate
25%—75% ammonium picrate—barium 65 nitrate

20%—80% charcoal—potassium chlorate
50%—50% tetryl—lead peroxide

With the inflammable bead applied and dried, further protective dips may be used, such as one or more dips in nitrocellulose 70 lacquer with drying between repeated dips. The protective dips may extend as far up on the fuse as desired.

An assembly in accordance with the present invention is illustrated in the accompanying 75 drawing wherein 5 designates a conventional blasting cap and 6 a length of conventional safety fuse. The commonly employed safety fuse comprises a sheath 7 of waterproof material and a core 8 of powder or other suitable 80 ignition train material. An igniting bead 9 comprising a mass of such volume as to substantially completely span the end of the fuse, and to wholly close and seal the central channel in which the core 8 of ignition 85 train material is located, is secured by its own adhesive quality to the outer end of the fuse 6, and preferably the outer end of the fuse is concaved to receive this mass of igniting bead material. After the lacquer dips 7a 90 have been applied, it will be seen that these lacquer dips constitute a waterproofing sheath of inverted cup formation, completely 95 housing and enclosing the bead 9 and the outer end of the fuse 6, the material of the sheath so formed being of highly inflammable non-hygrosopic nature. It follows that the least touch of flame thereto will ignite this sheath and igniting bead 9, and the latter is in sufficient volume to substantially span the 100 entire outer end of the fuse and close and seal the powder train against the entry of moisture.

The essentials of the assembly, viz; cap 5, fuse 6, igniting bead 9, and lacquer or like dip or dips 7a being moisture proof by the nature of the assembly, there is full protection in spite of consumer irregularities. Ordinary paper cartons may be used for packing and the separate assemblies may be so staggered in 105 packing that no two caps are in direct contact. The consumer need only remove an assembly, insert the cap end in the dynamite, load his hole and apply the slightest flame to the igniting bead on the open fuse end. He has 110 obviously avoided the hazards and inconveniences previously described.

While the use of the whole assembly will give the best results for the reasons stated, it is apparent that the use of a fuse having a 115 waterproofing bead or a waterproofing and ignition bead is desirable whether the whole assembly be used or not and consequently it is to be understood that that thought alone is within the purview of the invention.

Further, I wish it understood that I recognize the possibility of causing the bead 9 to comprise a material such as any of the well known safety match compositions adapted to be ignited by friction so that no match need 120

be used in windy weather. Such match composition could be covered with a waterproofing dip of nitrocellulose lacquer or other suitable material to repel moisture.

6 Having described my invention, what I claim is:

1. In combination, a safety fuse comprising a moisture proof sheath having an opening formed therethrough, an ignition train 10 in said opening, said sheath having a concaved outer end, an igniting bead of highly inflammable material, oval in cross section, seated in the concaved outer end of the fuse with its long axis disposed transversely of said fuse, 15 said bead spanning substantially the entire outer end of the sheath and completely sealing the ignition train opening thereof.

2. A structure as recited in claim 1 in combination with a dip of highly inflammable 20 waterproof and non-hygroscopic material adhesively secured to the outer end of the sheath, and said bead, and aiding in holding the latter in place, substantially as described.

3. A structure as recited in claim 1 wherein 25 said fuse is of a predetermined length and square cut at its inner end, and a blasting cap crimped thereon with the inner end of the fuse in close contact with the charge of the blasting cap, the whole constituting a pre-formed article of manufacture.

4. In combination, a safety fuse comprising a moisture proof sheath having an opening formed therethrough, an ignition train in said opening, a relatively thick bead of inflammable and adhesive material of such volume and width as to completely cover the 35 said opening of the sheath, the end of the sheath being made of concaved formation for the reception of said bead, and an adhesive dip 40 of inflammable material which completely encloses the outer end of the sheath and said bead.

5. A structure as recited in claim 4 wherein the said bead is of a width to span the entire 45 outer end of the sheath.

6. In combination, a safety fuse comprising a moisture proof sheath having an opening formed therethrough, an ignition train in said opening, a relatively thick bead of inflammable and adhesive material of such volume 50 and width as to completely cover the said opening of said sheath, and an adhesive dip of inflammable material which completely encloses the outer end of the sheath and said bead, said fuse being of predetermined length and square cut at its inner end, and a blasting cap crimped thereon with the inner end 55 of the fuse in close contact with the charge of the blasting cap, the whole constituting a preformed article of manufacture.

7. In combination, a section of safety fuse of a predetermined length having the usual ignition train extending centrally therethrough, a bead of inflammable and moisture 60 proof material upon the outer end of the fuse,

a sealing dip waterproofing composition covering said bead and the outer end of the safety fuse, a blasting cap upon the inner end of the fuse, the inner end of said fuse being square cut and seated firmly upon the explosive charge of the blasting cap, said blasting cap being crimped upon said fuse prior to 70 shipment and the whole constituting a pre-formed article of manufacture and explosive assembly.

75 In testimony whereof I affix my signature.

JOHN SWENEHART.
